UNITED STATES PATENT OFFICE.

WILLIAM F. BLANEY, OF NEWARK, NEW JERSEY, ASSIGNOR TO THE TURNER TANNING MACHINERY COMPANY, OF PEABODY, MASSACHUSETTS, A CORPORATION OF MAINE.

LEATHER-WORKING MACHINE.

Application filed September 12, 1923. Serial No. 662,219.

This invention relates to machines for treating hides, skins and leather of that class in which a bed roll is employed to support the work while a bladed cylinder or roll operates upon the work supported by the bed roll.

In shaving machines, as heretofore constructed, the cutting cylinder has ordinarily been of such a dimension as to present an effective cutting surface approximately twelve inches in length, although more recently larger cylinders have been employed with an effective cutting surface of about two feet in length. In operating with either machine, it is necessary for the operator to shave a portion of a skin and to shift the skin repeatedly in both lateral and longitudinal directions to operate upon adjacent portions, the whole operation of shaving a skin requiring the greatest skill in order to obtain uniformity throughout all portions of the shaved skin and to avoid the presence of ridges or scores or other lines of demarcation between adjacent areas successively operated upon. Moreover, the shaving of perforated portions of the skin and of the margins, and especially of those parts which form projections or tabs extending from the body portions, make great demands upon the skill and patience of the operator. It is not surprising, therefore, that operators on shaving machines are among the most highly paid employees of leather manufacturing plants.

It is an object of this invention to provide a shaving machine of relatively great capacity, when compared with prior machines, which may be operated satisfactorily by the ordinary workman without the exercise of expert knowledge. It is a further object of the invention to secure uniformity and a high grade of excellence in the product of the machine, even in operations upon rather medium grades of skins and hides such as those having perforated portions.

With the above and other objects in view and in accordance with important features of the invention means is provided independent of the feed rolls and of the shaving cylinder for spreading and smoothing portions of the skin or hide before it is operated upon by the shaving cylinder so that eventually all portions of the skin or hide are

carried in extended condition to the cylinder without any folds or wrinkles which would interfere with perfect cutting by the cylinder blades in the shaving operations. Preferably, and as shown, the spreading means comprises a spreading roll or cylinder in co-operation with a surface upon which the hide or skin is extended through the operation of the rotating spreading roll. In the illustrative construction the spreader surface is provided by a bed plate which is yieldingly mounted so as to accommodate itself automatically to variations in the thickness of the hide or skin being operated upon. Conveniently, the bed plate is mounted upon the same support which carries the supporting feed roll over which the skin is folded approximately midway of its length in position for the beginning of operations, and by this support the bed plate is moved into co-operative relation with respect to the spreader roll. Because of the effectiveness of the illustrated machine and particularly of the spreading means, it is possible to operate upon the full width of a skin at one time. Hence approximately one half of the skin may be shaved by the illustrated machine at one operation, and the remainder similarly treated at a succeeding operation. There is thus accomplished in two operations an amount of work which has heretofore required much laborious effort and many operations with a shifting of the skin between each operation.

Other features of the invention and novel combinations of parts will be described in the detailed specification and pointed out in the appended claims. In the drawings,

Fig. 1 is an end view of a machine showing one embodiment of the invention;

Fig. 2 is a front view of one end portion of the machine shown in Fig. 1;

Fig. 3 is a sectional view in a direction from front to rear of the machine showing the parts in working position; and

Fig. 4 is a view similar to Fig. 3 with the supporting roll in work receiving position.

In the drawings the machine is shown as provided with relatively heavy end frames which carry bearings for the various rolls and cylinders which constitute the work operating parts of the machine. The work may consist of hides, kips, skins or pieces

2

of leather of various origins, and no limitation is to be inferred because of the use of the word "skins" in referring to the work. Supported in the upper portions of the end frames is a feed roll 8, sometimes called a pinch roll, carried by blocks 10 slidably mounted in guideways 12, a spring 14 being provided for pressing each block 10 yieldingly in a downward direction to hold the feed roll 8 yieldingly against a co-operating feed roll 16. Preferably, the latter feed roll is mounted in bearings at the upper ends of arms 18 pivoted at 20 in the end frames 6. When the machine is at rest the arms 18 support the feed roll 16 in the position shown in Fig. 4, that is, spaced from the feed roll 8 so that the work may be readily introduced by folding it over the roll 16, as indicated in said figure. For operating the arms 18 there is provided a bell crank mechanism indicated at 22 (Fig. 1) to which is pivotally attached a link 24 which passes loosely through a projection 28 on a second link 30 pivoted at 32 to the lower end of the arm 18. Interposed between the link 24 and the link 30 is a spring 34 whereby power from the shaft 36 is yieldingly applied to the arms 18. When the bell crank 22 is moved to the position shown in Fig. 1 the arm 18 is rocked to carry the feed roll 16 into position beneath the upper feed roll 8 whereby the skin in position on the lower feed roll is firmly engaged so that it will be fed upon rotation of the feed rolls. Preferably the supporting feed roll 16 has a rubber portion 38 to support and feed the work.

Mounted in the end frame 6 to the rear and below the upper feed roll 8 is a cylinder 40 having cutting blades 42 arranged helically on its surface according to the usual construction in which the blades extend in opposite directions from the longitudinal center of the cylinder. These blades have the sharpened edges usual in cylinders utilized for fleshing or shaving operations on skins or hides. When the feed roll 16 is moved into operative position, indicated in Figs. 1 and 3, the skin is pressed against the surface of the cylinder 40 by the rubber-covered feed roll 16 and subjected to a shaving operation at the same time that it is being fed by the rolls 8 and 16. In the illustrative construction the feed rolls 8 and 16 turn in the directions indicated by the arrows in Fig. 3 to feed the work out of the machine during the operation of the shaving cylinder 40. Hence, only that part of the skin below the point of contact with the cylinder 40 at the time that the machine is started in operation is operated upon while the feed roll 16 is maintained in operative position. The machine must then be stopped with the feed roll 16 in the open position of Fig. 4, and the work reintroduced with the unshaved part suspended over the feed roll

16 below the level of a plane passing through the axes of the feed roll 16 and the cylinder 40. Upon starting the machine again the second half of the skin is shaved and simultaneously fed out of the machine through the action of the feed rolls 8, 16.

In order that the skin may be properly operated upon during the shaving operation it is necessary to provide means for spreading the skin in extended condition. Not only should all folds in the skin be removed by the spreading means but the tabs or other projecting portions around the peripheral portions of the skin and also any perforated parts should be held extended so as to insure proper operation of the cutting means. In the illustrative construction the means for spreading the skin being operated upon comprises a cylinder 50 having blades 52 arranged helically on the surface of the cylinder, the edges of the blades being dull or somewhat rounded, retaining, however, sufficient "edge" to engage the skin for a spreading and more or less stretching operation in order that the skin may be properly extended for the operation of the cutting cylinder. It will be understood that the helically arranged blades 52 extend in opposite directions from the lengthwise center of the cylinder so as to spread the skin laterally. Means is provided for driving the cylinder 50, the said means comprising, in the illustrated construction, a belt 54 arranged to engage a pulley 56 on the end of the shaft of the cylinder 50, the opposite end of the belt passing around a pulley 58 on a counter shaft 60 driven through a train of gears including gear 62 on the shaft 36. For co-operation with the spreading cylinder 50 there is provided in the illustrated machine, a bed plate 70 which extends longitudinally of the cylinder 50 and is pivotally supported by arms or extensions 72 (Fig. 2) having pivotal connection with the shaft or trunnion portions of the feed roll 16. As shown, the bed plate 70 is concaved transversely (Fig. 3) so that a curved surface of considerable extent is provided for effective co-operation with the periphery of the spreading cylinder 50 in spreading operations upon the skin.

Preferably, the bed plate 70 is backed by spring means which will enable the bed plate to adjust itself automatically to variations in the thickness of the skins or hides being operated upon. In the construction shown the supporting arms 18 are each provided with a projection 76 having a stud or boss to seat one end of a spring 78, the other end of which engages with a corresponding projection or boss on the rear surface of the bed plate 70. In a projecting rib or flange 80 on the arm 72 is a perforation which is interiorly screw-threaded to receive a set screw or bolt 82 which carries a lock nut 84 so that the screw or bolt may

be properly adjusted to secure proper tension of the spring 78, the end of the bolt or screw being normally in contact with a stop or abutment 86 fixedly secured to or integral with the corresponding arm 18. It will be understood that by adjusting the screws or bolts 82 the springs 78 may be placed under any desired amount of tension so that there will be an initial tension in the springs, one at each end of the bed plate, tending to hold the bed plate 70 with sufficient resistance against the spreading roll 50 to insure proper co-operation between these parts in spreading operations on the skin or hide. From the foregoing description it will be clear that the bed plate 70 moves with the feed roll 16 when the supporting arms 18 move to open position, which occurs when the machine comes to rest after each operation in accordance with the usual and well known mode of operation of this type of machine.

In operating with the machine, a skin or hide is thrown over the lower feed roll 16 and over the bed plate 70 while the arms 18 are in the open position shown in Fig. 4, the skin being folded over the roll 16 along a line corresponding approximately to a central fold in the skin or hide. It will be understood that all of the rolls and cylinders may be of a length to accommodate and operate upon the largest skins or hides when fully spread out. Upon starting the machine the arms 18 are at once operated to move the feed roll 16 and the bed plate 70 into the closed position shown in Figs. 1 and 3 where they are held while all of the rolls are rotated to feed and to operate on the skin or hide. In the construction shown the feed rolls 8 and 16 rotate in the direction of the arrows to feed the skin or hide out of the machine and as the skin moves along under the action of the feed rollers the cylinders 40 and 50 perform their operations of spreading and shaving the skin or hide, the spreading operation taking place in such relation to the operation of the cylinder 40 that the skin is properly spread for the operation of the cutting cylinder 40. When the skin has been completely fed from the machine the latter is stopped by releasing the usual treadle, whereupon the supporting arms 18 move to the open position of Fig. 4 so that the skin may be reintroduced into the machine with the unshaved part thrown over the feed roll 18 and the bed plate 70 in position for operation by the cutting cylinder 40, care being taken that the unshaved portion of the skin or hide is positioned below a line joining the centers of the feed roll 16 and the cutting cylinder 40. This second operation of the machine completes the shaving or fleshing of the skin or hide. It will be observed that the shaving of the skin or

hide by this machine calls for little in the way of expert knowledge, such as is absolutely necessary in shaving operations where the regular commercial machines are employed. Furthermore, the labor of the operator is reduced simply to the introduction and removal of the work, whereas in the commercial operations, as practised today, the operator must hold the skins and exercise very considerable tension on the skins while they are being shaved. By means of applicant's invention there is secured uniformity in the thickness of the shaved skins or hides and also a greatly increased output.

It is to be understood that the spreading means herein disclosed is not limited in its application to shaving machines but may be applied to machines for fleshing, unhairing, scrubbing, brushing, cleaning, setting, pulling-out, and other analogous uses.

Having thus described my invention, what I claim as new and desire to secure by Letters Patent of the United States is:—

1. In a machine of the character described, a work operating member, feed rolls for feeding the work, means comprising a rotary member for spreading and smoothing the work for the operation of said operating member, and a member movable to press the work against the rotary member.

2. In a machine of the character described, a member for operating on work, feed rolls for feeding the work, and spreading means comprising a smooth-surfaced bed plate over which the work is moved by the feed rolls while being spread in extended relation before it passes to the feed rollers and into the field of operation of said member.

3. In a machine of the character described, a member for operating on work, feed rolls for feeding the work, and spreading means for spreading the work in extended relation for the operation of said member, said means comprising a spreading roll in co-operation with a member over which the work is spread by the spreading roll.

4. In a machine of the character described a cutting cylinder, upper and lower feed rolls for feeding the skin or hide past the cutting cylinder, means for supporting the lower feed roll so that it may be moved from work receiving to work presenting position, a bed plate carried by the supporting means and having a curved supporting surface upon which the skin or hide may be spread, and a spreader roll arranged for co-operation with the bed plate to spread the skin or hide for the operation thereon of the cutting roll or cylinder.

5. In a machine of the character described, a cutting cylinder, feed rolls for feeding the work past the cutting cylinder, a spreading roll, and a member arranged for co-opera-

- 4
- tion with the spreading roll to spread the work in extended condition prior to the operation thereon of the cutting cylinder.
6. In a machine of the character described, means for operating on work, upper and lower feed rolls for feeding the work past said means, a spreading cylinder located at one side of said means, a support for the lower feed roll movable to open position so that the work may be placed over the lower feed roll, and a member carried by the said support and movable into co-operative relation with the spreader roll to effect spreading of the work.
15. 7. In a machine of the character described, means for operating on work, feed rolls for feeding the work past said means, a spreader roll located to operate on the work to spread the same in extended condition, a member having a surface for co-operation with the spreader roll, and a support for said member movable to carry it from work receiving position to work presenting position with respect to the spreader roll.
25. 8. In a machine of the character described, means for operating on work, feed rolls for moving the work past said means and for supporting the work during the operation of said means, a spreader roll, and a member having a curved surface for co-operation with the spreader roll, said member and spreader roll being relatively movable in a direction toward and from each other so that the work may be introduced while they are in opened position and subsequently operated upon to spread the same when they are brought into co-operative relation.
40. 9. In a machine of the character described, a cutting cylinder, feed rolls for feeding the work and for supporting it for the action of the cutting cylinder, and means comprising a spreading roll stationary in space and rotatable with the feed rolls and in a direction opposite to that of the feed of the work for spreading the work prior to the operation of the cutting cylinder.
50. 10. In a machine of the character described, a cutting cylinder, feed rolls for feeding the work and for supporting it for the action of the cutting cylinder, and spreading means comprising a rotatable member and a bed plate having a surface of substantial extent over which the work is moved by the feed rolls while being spread in extended relation before it passes to the feed rolls and into the field of operation of the cutting cylinder.
60. 11. In a machine of the character described, a cutting cylinder, feed rolls for feeding the work and for supporting it for the action of the cutting cylinder, and spreading means for spreading the skin in extended relation prior to the operation of the cutting cylinder, said means comprising a bladed cylinder in co-operation with a bed plate which is stationary while the skin is spread thereover by the spreading roll.
12. In a shaving machine, a cutting cylinder for fleshing or shaving skins or hides, upper and lower feed rolls for feeding the skin or hide past the cutting cylinder, a pair of arms for supporting the lower feed roll so that it may be moved from work receiving to work presenting position, a bed plate carried by the supporting arms and having a curved supporting surface upon which the skin or hide may be moved by the feed rolls to be spread in extended condition, and a spreader roll arranged for co-operation with the bed plate to spread the skin or hide for the operation thereon of the cutting roll or cylinder.
15. 13. In a machine of the character described, a cutting cylinder, feed rolls for feeding the work past the cutting cylinder, a spreading roll, a bed plate arranged for co-operation with the spreading roll, and means for yieldingly backing the bed plate so that the spreading means accommodates itself automatically to variations in the thickness of the work.
20. 14. In a machine for shaving hides, skins, leather or other similar pieces of work, a cutting cylinder, upper and lower feed rolls for feeding the work past the cutting cylinder, a spreading cylinder located at one side of the cutting cylinder, a support for the lower feed roll movable to open position so that the work may be placed over the lower feed roll, and a bed plate carried by the said support and movable therewith into co-operative relation with the spreader roll.
25. 15. In a machine for shaving hides, skins, leather or other similar pieces of work, a cutting cylinder, feed rolls for feeding the work past the cutting cylinder, a spreader roll located to operate on the work to spread the same in extended condition, a bed plate having a curved surface for co-operation with the spreader roll, and a support for the bed plate movable to carry it from work receiving position to work presenting position with respect to the spreader roll.
30. 16. In a machine for shaving hides, skins, leather or other similar pieces of work, a cutting cylinder, feed rolls for moving the work past the cutting cylinder and for supporting the work during the operation of the cutting cylinder, a spreader roll, and a bed plate having a curved surface for co-operation with the spreader roll, said bed plate and spreader roll being relatively movable in a direction toward and from each other so that the work may be introduced while they are in opened position and subsequently operated upon to spread the same when they are brought into co-operative relation.
35. In testimony whereof I have signed my name to this specification.
- WILLIAM F. BLANEY.
